Primary Examiner — Keith J Wilson

(57) **CLAIM**

The ornamental design for a filter endcap applicable to bottom of filter cartridge, as shown.

DESCRIPTION

FIG. 1 is a top perspective view of a filter endcap applicable to bottom of filter cartridge;

FIG. 2 is a bottom perspective view of the filter endcap applicable to bottom of filter cartridge depicted in FIG. 1; FIG. 3 is a bottom view of the filter endcap applicable to bottom of filter cartridge depicted in FIG. 1;

FIG. 4 is a front view of the filter endcap applicable to bottom of filter cartridge depicted in FIG. 1;

FIG. 5 is a rear view of the filter endcap applicable to bottom of filter cartridge depicted in FIG. 1;

FIG. 6 is a left side view of the filter endcap applicable to bottom of filter cartridge depicted in FIG. 1;

FIG. 7 is a right side view of the filter endcap applicable to bottom of filter cartridge depicted in FIG. 1; and,

FIG. 8 is an exploded environmental view of a filter showing an environment of the filter endcap applicable to bottom of filter cartridge depicted in FIG. 1 in broken lines.

The dash-dot lines showing in the figures are used to define the claimed design, while the broken lines showing in the figures are for illustrative purposes only and form no part of the claimed design.
